UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPGRAPHICAL MACHINE.

1,099,448.

Specification of Letters Patent.

Patented June 9, 1914.

Application filed December 17, 1912. Serial No. 737,168.

To all whom it may concern:

Be it known that I, DAVID S. KENNEDY, a citizen of the United States, and a resident of the borough of Brooklyn, county of Kings, and State of New York, have invented a new and useful Improvement in Typographical Machines, of which the following is a specification.

My invention relates to machines in which printing slugs or bars are cast in a slotted mold and then delivered therefrom by an ejector blade which advances against the edge of the slug. In many of these machines the molds are variable or adjustable in length in order to produce slugs for printing columns or pages of different widths; and in connection with such an adjustable mold is frequently employed a composite ejector having its parts so constructed and combined that its operative portion may be varied in width to correspond with changes in the length of the mold slot. As illustrated for instance in Letters Patent of the United States, No. 967,976 to John R. Rogers, the ejector blade is composed of a series of parallel sections arranged edge to edge, and a mechanism is provided whereby any desired number of these sections can be connected with the actuating slide, while the others are left free therefrom. In the operation of such machines, it sometimes occurs, at the hands of an inexperienced or careless operator, that an attempt is made to connect or disconnect the sections at an improper time, and generally when the machine is in operation. This attempt sometimes results in injury to the parts, or in inconvenience and loss of time, which disadvantages it is the object of my invention to prevent. To this end I construct the parts so that the ejector sections may be connected with and disconnected from the actuating devices only when the parts are in a predetermined position, preferably when the machine is at rest and when the ejector is withdrawn from the mold.

In the accompanying drawings, I have illustrated my invention in preferred form and by way of example, and as applied to the style of machine already mentioned, but obviously many changes and variations therein, and in its mode of application, will

suggest themselves to those skilled in the art and still be comprised within its scope. 55 Generally speaking, I desire it to be understood that I do not limit myself to any specific form or embodiment, except in so far as such limitations are specified in the claims.

60 Referring to the drawings: Figure 1 is a perspective side view of the mold and ejecting devices, partly in section and partly broken away, having my invention applied thereto; Fig. 2 is a sectional view on an enlarged scale, taken substantially on the line 2-2 in Fig. 1; Fig. 3 is a view of some of the parts, similar to Fig. 1; Fig. 4 is a section taken substantially on the line 4-4 in Fig. 2; and Fig. 5 is a detached view of an 70 ejector section and its actuating member.

As in the said Rogers patent, the mold disk A is provided with the usual slotted mold B and is mounted upon the slide C, and the slide D is arranged to reciprocate 75 horizontally on the slide C for the purpose of actuating the ejector. The ejector proper E comprises a series of parallel blades or sections e, which sections are arranged one above another, and are guided between the 80 vertical face of the mold slide C on one side and the vertical plate F on the opposite side. The several sections are free to move forward and backward independently, and also so that any desired number may be brought 85 into action jointly, to form an ejector of a vertical width corresponding to the length of the slug which is being cast in the machine, while the other sections remain inactive in their inner or backward position. 90 Each ejector section e is actuated by a corresponding member G, which members are mounted in grooves c¹ formed in the mold slide C. In order that any required number of the sections e may be coupled to 95 the actuating slide D, while the other sections remain free, I employ the vertically movable bar H, carried by the slide D, and having its lower end arranged to travel forward and backward on the rod I attached to 100 the vertical slide J. The parts and operation so far described are or may be substantially the same as those disclosed in the said Rogers patent, wherein also the same letters of reference are employed.

105 The vertical slide J may be shifted by the

pivoted hand lever K, which is provided with a spring pressed locking handle K¹ adapted to engage teeth on the stationary sector K², whereby the parts are held in position to cause the selection of any desired number of ejector sections e. An indicator L connected to the lever K assists the operator in adjusting the parts. The bar H is thus adapted to rise and fall behind the members G, and may be moved upward or downward to such position that it will drive forward any desired number of sections without affecting the others. The retraction of the operative sections is effected by means of shoulders g on the rear ends of the members G which engage behind the vertical shoulder d on the slide D. So far as described, the parts are of the usual construction and constitute no part of my present invention.

As previously stated, it frequently happens that an attempt to change the adjustment or width of the ejector at improper times results in injury thereto or in other inconvenience or delay. I have therefore provided additional means, whereby the change may be made only when the machine is at rest and when the ejector E has been withdrawn from its normal position within the mold D. To this end I provide the sliding bar H with an inwardly projecting stud P, which in the said position of the parts is free to move upward and downward in the vertical groove R formed in the mold slide C, as shown in Fig. 3. When the ejector slide D advances, the bar H moves forward and its stud P enters and engages one of the grooves c¹, as shown in Figs. 1, 2 and 4, thereby locking the bar H against vertical movement and thus preventing a change in the width of the ejector E.

As before stated, in the ordinary position of rest, the ejector E, or the effective portion thereof, is located partly within the mold B. If now it be desired to alter the adjustment of the ejector, this can be effected only by moving it rearwardly, or until the stud P is restored to the groove R, when the bar H may be again shifted vertically to the required extent. The preferred means employed for this purpose are the handle S connected to the arm S¹, which is mounted on the same shaft with the ejector lever S², which in turn is connected to the ejector slide D by the link S³. In this position of the parts (Fig. 3), the manipulation of the lever K effects the vertical movement of the bar H, so as to select a greater or less number of sections e in order to vary the width of the ejector E.

Having thus described my invention, its construction and mode of operation, what I claim and desire to secure by Letters Patent of the United States is, as follows:

1. In a typographical machine, the combination of a movable ejector variable in

width, a single adjusting device for controlling the width of said ejector when the parts are in predetermined position, and means for preventing the operation of said device at any other time.

2. In a typographical machine, the combination of a movable ejector comprising a plurality of sections, a single adjusting device for selecting the desired number of sections when the parts are in predetermined position, and means for preventing the operation of said device at any other time.

3. In a typographical machine, the combination of a movable ejector comprising a plurality of sections, actuating means therefor, a single adjusting device for connecting the desired number of sections with the actuating means when the parts are in predetermined position, and means for preventing the operation of said device at any other time.

4. In a typographical machine, the combination of a movable ejector comprising a plurality of sections, actuating means therefor, a single adjusting device carried by said actuating means for controlling the connection of the sections therewith when the parts are in predetermined position, and means for preventing the operation of said device at any other time.

5. In a typographical machine, the combination of a movable ejector comprising a plurality of sections, a lateral support formed with longitudinal grooves and also with a transverse groove, and a connecting device movable both longitudinally and transversely of said support and provided with a projecting stud to engage in said grooves; whereby the transverse movement of said device is prevented except when its stud stands in the transverse groove.

6. In a typographical machine, the combination of an ejector comprising a plurality of sections, a corresponding plurality of actuating slides, a support formed with longitudinal grooves in which said slides move, and formed also with a transverse groove; and a connecting and actuating device movable both longitudinally and transversely of the support and provided with a projecting stud to engage in said grooves; whereby the transverse movement of said device is prevented except when its projecting stud stands in the transverse groove.

7. In a typographical machine, the combination of an ejector comprising a plurality of sections e, and a corresponding plurality of actuating slides G, a support C formed with longitudinal grooves c¹ in which the slides move and with the transverse groove R, and a connecting member H movable both longitudinally and transversely of the support C and provided with a projecting stud P to engage in said grooves; whereby the transverse movement

of the member H is prevented except when its projecting stud P stands in the transverse groove R.

8. In a typographical machine, the combination of an ejector comprising a plurality of independently movable sections, a transversely movable connecting device for selecting the desired number of sections and then movable therewith, and means for preventing the transverse movement of said device except when it occupies a predetermined position.

9. In a typographical machine, the combination of a mold, a movable ejector comprising a plurality of sections, the active ones of which stand normally within the mold, actuating means adapted to be connected to any desired number of the ejector sections, mechanism to prevent a change in such connection, and devices for withdrawing the active sections from the mold at will to render said mechanism inactive.

10. In a typographical machine, the combination of a mold, a movable ejector comprising a plurality of sections, the active

ones of which stand normally within the mold, actuating means, adjustable means for connecting any desired number of sections with the actuating means, mechanism to prevent the adjustment of said connecting means, and devices for withdrawing the active sections from the mold at will to render said mechanism inactive.

11. In a typographical machine, the combination of a mold, a movable ejector variable in width and adapted to stand normally within the mold, adjusting means for controlling the width of said ejector, mechanism to prevent the adjustment of said means, and devices for withdrawing the ejector from the mold at will to render said mechanism inactive.

In testimony whereof I hereunto set my hand this 12th day of December, 1912, in the presence of two attesting witnesses.

DAVID S. KENNEDY.
